CLAIM

The ornamental design for a vent clip holder for lip balm, as shown and described.

DESCRIPTION

FIG. 1 is a perspective of a vent clip.

FIG. 2 is a top plan view thereof.

FIG. 3 is a bottom plan view thereof.

FIG. 4 is a rear elevational view of the vent clip.

FIG. 5 is a left side view of a vent clip, the right-side view is a mirror image; and,

FIG. 6 is a front elevational view of a vent clip.

The broken lines are shown for the purpose of illustrating environmental subject matter and form no part of the claim.
